UNITED STATES PATENT OFFICE.

ORRIS H. NEWMAN, OF PEKIN, ILLINOIS.

SELECTIVE RINGING AND LOCKING DEVICE.

No. 821,820.

Specification of Letters Patent.

Patented May 29, 1906.

Application filed April 8, 1905. Serial No. 253,553.

To all whom it may concern:

Be it known that I, ORRIS H. NEWMAN, a citizen of the United States, residing at Pe-
kin, in the county of Tazewell and State of
Illinois, have invented certain new and use-
ful Improvements in Selective Ringing and
Locking Devices; and I do hereby declare
that the following is a full, clear, and exact
description of the invention, which will en-
able others skilled in the art to which it ap-
perts to make and use the same.

This invention has reference to an im-
proved telephone selective ringing device,
being more particularly adapted to phones on
independent lines; but the principle therein
embodied may be adapted to other signaling
systems.

One of the objects which I have in view is
selecting the various signals according to the
number of revolutions of a magneto by
means of which the signaling is done.

A further object of the invention is a se-
lector actuated by an armature-lever which
is moved through the instrumentality of a
magneto and to a controlling device adapted
for locking all of the receiver-hooks of the va-
rious phones on a line other than the one for
whom a call is made.

A further object of the invention is to pro-
vide a selector adapted to be actuated in a
step-by-step movement, an armature-lever
movable through the energizing of an elec-
tromagnet and provided with a suitable es-
capement for moving and controlling the
movement of the selector; a magneto for en-
erгizing the magnet to adapt the movement
of the armature-lever, and thereby the selec-
tor, and means controlled by the number of
revolutions imparted to the magneto for se-
lecting the phone desired to be called and the
ringing of the call-bell of such phone upon
the desired number of revolutions being im-
parted to the magneto.

The invention consists, further, of a selec-
tor-disk adapted to be moved through the ac-
tion of an armature-lever, an electromagnet
for intermittently oscillating the said lever
when the respective coils of said magnet are
energized and deenergized, a second lever,
means for holding the lever raised when the
said magnet is energized, a magneto for ener-
gizing the said magnet, means controlled by
the second lever for locking the receiver-hooks
of the phones not called and for releasing the
hook of the phone through which communi-
cation is desired, and means carried by the

said second lever coacting with the selector-
disk for stopping said disk in accordance with
the number of revolutions imparted to a magn-
eto when calling the respective phones. 60

With these and other objects in view, as
will hereinafter appear more fully, the inven-
tion consists in the novel construction and
arrangement of parts hereinafter described,
illustrated in the accompanying drawings, 65
and particularly pointed out in the appended
claims, it being understood that various
changes in the form, proportion, size, and
minor details may be made without depart-
ing from the spirit or sacrificing any of the 70
advantages of the invention.

In the accompanying drawings, Figure 1 is
a front elevation, somewhat reduced, of a
telephone such as my invention may be at-
tached to and having my improvements ap-
plied thereon, the cover, mouthpiece, and
neck, as well as several minor details of a 75
phone of this character, being omitted. Fig.
2 is a plan view, substantially full size, show-
ing in plan the selector which I employ, the
armature-lever and magnet for actuating the
same, together with the receiver-hook and 80
device for locking and releasing the same.
Fig. 3 is a side elevation in detail of parts for
holding the armature-lever raised when the
magnet is energized; and Fig. 4 is a front 85
elevation, partly in section, of the selector
and armature-lever, a portion of the receiver-
hook, and the means for locking the same.

In explanation of my invention it is well to 90
call attention to the fact that the same is
preferably adapted to independent telephone
systems, such as are used in rural districts,
where each person is his own central office
and may call any of the several persons who 95
may be connected with his phone by revolv-
ing a magneto a given number of revolutions
for energizing the line to effect the adjust-
ment of the selector to circuit-closing posi-
tion of the party with whom connection is 100
desired, when his call-bell will ring and con-
tinue to ring until his receiver is removed
from its hook, when the circuit in which the
bell is located will be opened by the auto-
matic raising of the hook, or the magneto is 105
turned by the party calling to cause the selec-
tor to return to its initial position, all of which
will be more fully explained. No attempt has
been made to illustrate a series of phones and
the connection between the same, as it is be- 110
lieved these features are all well understood
and need no further illustration or explana-

tion here. It is also believed that the wiring and connections between the parts of the device to illustrate the mode of energizing the magnet and wires connecting the several parts will be readily understood.

Similar characters of reference are employed to indicate corresponding parts throughout the several figures of the drawings.

- 10 In the drawings, 1 denotes a suitable casing, such as are in use for phones on independent telephone systems. The same is divided by means of partitions 2 and 3 and also provided with a shelf or rest 4. In the 15 lower compartment of this case, formed by the partition or shelf 2, is a series of electric batteries of any well-known construction, (indicated as 5, 6, and 7,) battery 5 being employed as a part of the circuit in which 20 my improvements are arranged, the remaining two serving as a part of the usual connections in a phone of this character. Supported by the partition or shelf 2 is shown a magneto 8, being similar to those used on telephone-circuits and consisting of the usual 25 mechanical parts and adapted to be actuated for energizing the magnets and lines connected therewith by means of a handle 9, carried exteriorly of the casing 1 and connected with 30 the armature in the usual way.

10 indicates a lever pivoted at 11, the same being supported within the casing, as seen in Fig. 1, and serving as the receiver-hook of a receiver 12. The forward end of the lever 35 passes out through a slot in the wall of the casing (not shown) and is provided with a receiving portion 13 for the receiver, as shown. The lever 10 when the receiver is supported thereby is in its lowermost position; but when the receiver is removed a 40 spring 14 will raise the same, as is the custom in all phones, for the purpose of making the proper contact, so as to transmit sound, all of which is understood. There is no difference in the construction of this lever 10 45 from those in use, nor are the electric connections with the same any different from those in daily use. While the batteries, the receiver-hook, receiver, magneto, and connections of 50 such parts with the line-wires are of the usual construction, certain new and useful features are introduced for making and breaking a circuit by the lever, as well as locking the 55 position of all the levers of the phones not called.

At a suitable point on the partition or shelf 3 is a vertically-disposed bearing 15, which supports a revolvably-carried plate or selector-disk 16, the periphery of which is provided with ratchet-teeth 17, as shown. The disk is provided with an elongated aperture 18, and from the under side of the disk and at a suitable point projects a stud or finger 19, the purpose of which will be further explained. Also supported by the shelf 3 is

seen an electromagnet 20, composed of the usual coils 21 and 22. 24 denotes an "armature-lever," so called by reason of an extension 25 from the body of the armature 24, having a pair of escapement-teeth or engaging portions 26 and 27. The said armature-lever 24 is fulcrumed in the ordinary way in front of the poles of the magnet 20 and is adapted when the poles are energized and de-energized to oscillate the said lever 24 and 70 cause the teeth 26 and 27 thereof to engage and advance the selector-disk 16 in a step-by-step movement, the tooth 26 advancing the disk one tooth or notch at a time, while the tooth 27 insures that the disk will move 80 only one tooth at a time. Electrical connectors are made between the coils 21 and 22 and the magneto 8 by means of the wires 28 and 29, the former leading from coil 21, while the latter leads from the coil 22. Thus it will 85 be seen as the crank 9 is turned the wires 28 and 29 will transmit an alternating current from the magneto to the magnet, thereby alternately energizing and de-energizing the coils 21 and 22 of the magnet, which will 90 in turn alternately attract the armature-lever 24 and through the same, or rather the teeth 26 and 27 thereof, intermittently advance the selector-disk 16 in a step-by-step movement. The said disk is prevented from backward 95 movement by means of a ratchet-arm 30, substantially as seen in Fig. 2.

31 indicates a lever, pivoted at 32 in a suitable standard, supported on the shelf 3 and extending forwardly some distance, the front end passing through a vertically-movable spindle 31^a, reciprocally carried in the bearing 15. (See Fig. 4.) The end of this lever at predetermined intervals is adapted to close an electric circuit for ringing a call-bell. Said lever is controlled more or less by means of a forked lever 33, a portion 34 of which the lever is carried over, and the lever 33, through weighted extensions 35, is pivotally supported at 36 in standards 37, (omitted in Fig. 1 110 for the purpose of disclosing other features,) and said lever is provided with extensions 38, which when the poles of the magnet 20 are energized are alternately attracted to such poles for raising the forward end of the lever 115 31, to which is operatively connected a depending arm 39, the arm 39 being attached or secured in a suitable way to the upper end of the spindle 31^a, which insures it being simultaneously raised or lowered at the same 120 time the lever 31 is raised or lowered. The lower end of the arm 39 rides above the revolvable selector-disk 16 to govern the downward movement of the spindle 31^a and the lever 31, which will drop a given distance 125 when the magnet 20 is de-energized; but when the aperture 18 of the disk 16 is coincident with the arm 39 and the magneto is stopped, the arm will descend in the movement of the spindle 31^a and the lever 31 into the aperture 130

aforesaid of the disk, permitting the lever to drop a much greater distance and by so doing make a suitable contact with parts to be described as to complete an electric circuit with the call-bell of the party whose selector-disk and arm 39 are adjusted to the number of revolutions imparted to the magneto. To the pivotal point of the lever 31 is connected an electric wire 40, which at its opposite and is connected with the battery 5 at 41.

It will be understood as the magneto is revolved the coils 21 and 22 are alternately energized and deenergized in the manner specified, which will have a tendency, through the arms 38 of the lever 33, to raise the forward end of the lever 31. For example, if the selector-disk 16 and the arm 39 are adjusted to ten revolutions of the magneto 8 and the same is revolved only nine times when the magneto is released the lever 31 here shown would drop into a position with the lower end of the arm 39 resting on the face of the disk 16, causing the end of the lever 31 to engage with a contact-plate 42, supported by the shelf 3, and close a circuit 43, leading through a magnet 44, supported by the shelf 4, to the battery 5 at 46 and back to the lever through the wire 40. Closing a circuit through the magnet 44, it attracts an armature-lever 47, holding the same until the lever 31 is again raised by the action of the magnet for breaking the circuit through the wire 43. The actuation of the lever 47 moves the forward or upper end thereof through a slot 48 in a cylinder 49, supported by the wall of the casing 1, and into a notch 50 in a plunger 51, movable in the said cylinder, which will lock the position of the plunger and, as the lower end thereof is normally in juxtaposition to the receiver hook or lever, prevent the same from being raised on the removal of the receiver, so that it will be practically impossible for any one to break in on a line when in use except by the revolving of his magneto, when any or all who are using the line will be apprised of this fact, which will necessitate the readjustment of all the selector-disks. Also a party may first ascertain whether or not the line is in use by removing his receiver, and if his receiver-hook does not rise he may easily learn that the line is in use. Now if the magneto is revolved ten times it will indicate that No. 10 phone is desired. In this event all selector-disks except No. 10 will stop in positions with the arm 39 resting on the upper face of the disks for the purpose of locking the receiver-hooks, as has been described, while on No. 10 the disk will stop with its aperture in alinement with the lower end of arm 39, so that when the magnet 20 is deenergized the arm 39 of the lever will drop through the aperture 18 of the disk, carrying the lever down to a point where the end thereof will pass the contact 42 and engage a supple-

mental contact-plate 52, supported in the same manner as contact 42, but separated from the same by some suitable insulation, closing a circuit through a wire 53, leading to a contact 54 on the receiver hook or lever 10, 70 which when the lever is in its lowermost position contacts with a contact 55, supported by the shelf 4, from which a wire 56 extends to a call-bell 57, connected by a wire 58 to the battery 5 at 46, the circuit being completed through the wire 40 from the battery 5 to the lever 31, as described. In the position just described the call-bell will continue to ring until the party called shall take down his receiver, when the contacts 54 and 55 80 will be separated by the raising of the lever 10 through the action of the spring 14. When through talking and the receiver is again replaced on its hook, the bell will ring until either the sender (whose duty it is) or receiver shall impart a few more revolutions to his magneto for the purpose of throwing the selector-disks to their initial positions.

The illustrations of the device are intended to show a system where twelve phones are arranged in a circuit. However, no limitation is placed on the number of phones which may be used in a circuit, so that thirteen turns of a magneto will impart one complete revolution to the selector-disks 16 through the 95 armature-lever 24. The selector-disk, as well as the operative parts of the device here shown, are adjusted to ten (10) turns or revolutions of the magneto—that is, ten complete revolutions of the magneto will place the aperture 18 of the disk coincident with the lower end of the arm 39, adapting the arm 39 and its lever when the magnet 20 is deenergized to make its full drop to complete the circuit in the manner specified to the call-bell. It is 100 intended that as each person uses a phone he will when finishing his talk revolve his magneto an additional number of revolutions to make a complete revolution of all the disks in the series. In this instance, as was 105 stated, it will take thirteen turns of the magneto. On the completion of the full rotation of the disk the lug 19 thereof will engage with the upper free end of a bell-crank lever 59, pivoted to the shelf 3, the opposite end of 110 which when the magneto is being actuated is held beneath a depending arm 60 of a crank which passes through the lever 31 and has its ends journaled in standards 61. (See Fig. 2; omitted in Fig. 1, so as to disclose 115 other features.) The energizing of the magnet 20 and the lever 33 in raising the lever 31 will throw the arm 60 forward over the extension of the crank 59 (see Fig. 4) and lock the crank, so that the lug 19 of the disk will 120 be prevented from passing; but upon stopping the magneto and again starting, the lug 19 of the disk will move past the bell-crank lever 59 before it can be prevented from doing so by the action of the arm 60 in en- 125

gaging the said crank, as in practice it has been found that the disks will move slightly quicker than the lever on starting.

Upon the attraction of the armature-lever 5 47 to lock the plunger 51 were some means not provided to release the same from the plunger immediately upon the deenergizing of the magnet 44 the said plunger would remain locked, and so to insure its returning to its 10 normal position after the release of the magneto and the return of all parts to their normal positions I provide the spring 62, attached to the lower end of the lever 47 and to the side of the casing 1.

15 To overcome the locking of the receiver-hook of the party calling, means is contemplated which could be used to facilitate in holding the receiver-hook raised during the operation of a magneto; but this might prove 20 impracticable, for the reason that the party calling might forget to adjust such a device, and thereby leave the line open. So in the present arrangement a party calling will raise slightly the receiver-hook of his phone until 25 the desired number of revolutions have been imparted to the magneto to prevent the locking of his phone, all of which it is believed will be understood.

The position of phones on a wall or bracket 30 is usually in such a position that a party desiring to use the phone naturally has to reach up, so that the position of the handle 9 would be normally as seen in Fig. 1, and a complete revolution would be construed to mean when 35 the handle has been turned once to reassume the position shown, so that a person could hardly ever mistake the number of revolutions to be made, the parts operated by the handle being adjusted to such a position of 40 the same.

It is obvious from the foregoing that various changes and modifications may be made in the present device without departing from the principle and scope of the invention, and 45 I do not wish to be confined to the detail shown or described.

Having thus fully described my invention, what I claim, and desire to secure by Letters Patent of the United States, is—

50 1. In a device of the class described, the combination of an electromagnet, a selector-disk provided with an aperture, an armature-lever adapted to be oscillated during the alternate energizing and deenergizing of the 55 coils of the magnet, and provided with means for imparting a step-by-step movement to the disk, a lever pivotally supported at one end and having its opposite end in operative connection with an arm supported above the 60 said disk, the said arm adapted to have an invariable movement at intervals when it en-

gages the face of the disk; and a variable movement also at intervals, said lever being actuated by the energizing of said magnet and the parts being so arranged that the said 65 arm will pass through the aperture of said disk when the magnet is deenergized, and a magneto governing the movement of the disk according to the number of revolutions imparted to said magneto.

70 2. In a device of the class described, the combination of a receiver-hook, devices for locking said hook, a selector-disk for controlling said hook-locking devices, also a signaling-circuit, an electromagnet, a lever, and means for holding the lever raised upon the energizing of said magnet, and lowered when the magnet is deenergized, a regulating-stop in operative engagement with the lever and adapted to engage with the disk, and a magneto for energizing said magnet.

75 3. In a device of the class described, a selector-disk having an elongated aperture, an armature-lever for moving said disk, an electromagnet for energizing the said armature, means for energizing the magnet, a lever adapted to be controlled by the disk, contact-plates adapted to be engaged by the lever, one of such contact-plates in a circuit controlling a receiver-hook-locking device, and the other contact-plate in a circuit containing a signaling-bell.

80 4. In a device of the class described, a selector-disk having an elongated aperture, means for moving the disk in a step-by-step movement, a receiver-hook, a locking device for said hook, a lever, means for holding the lever raised at predetermined intervals, a contact-plate arranged in a circuit containing the receiver-hook-locking devices, and a stop 85 regulated by the body of the disk and aperture therein for controlling the engagement of the lever with the contact-plate.

85 5. In a device of the character described, the combination of a toothed selector-disk for controlling a signaling-circuit, also the movement of a receiver-hook, a magnet, means actuated by the energizing of the magnet for moving the disk, two electric circuits, one containing the call-bell, the other locking 100 devices for controlling the receiver-hook, means having a variable movement for closing both of said circuits at predetermined intervals, and means for energizing the said magnet.

105 In testimony whereof I affix my signature in presence of two witnesses.
